NONREFILLABLE BOTTLE

Joseph Nozar, Sr., Cleveland, Ohio

Application November 10, 1937, Serial No. 173,911

6 Claims. (Cl. 215—83)

This invention relates to certain new and useful improvements in non-refillable bottles.

The primary object of the invention is to provide a non-refillable bottle wherein a tensioned bottle closure plug is carried by a bottle cap with the cap having interlocking connection with a frangible flange on the neck of the bottle, the cap when in position on the bottle being prevented from removal therefrom by the introduction of the plug into the bottle neck which prevents separation of the interlocking connection between the cap and bottle neck and necessitates the breaking of the frangible flange on the bottle neck to permit removal of the cap and thereby destroying the bottle neck.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary perspective view of a non-refillable bottle constructed in accordance with the present invention, the bottle being preferably formed of glass and carrying a relatively thin frangible flange at the mouth thereof;

Figure 2 is a top plan view of the bottle cap showing diametrically opposite lugs for sliding interlocking reception on the flange of the bottle mouth;

Figure 3 is a bottom perspective view of the cap showing the diametrically opposite grooved lug at the open end of the cap for interlocking engagement with the flange on the bottle mouth;

Figure 4 is a fragmentary longitudinal sectional view of the bottle showing a sealing disk or gasket seated on an internal shoulder in the bottle neck below the bottle mouth flange;

Figure 5 is a longitudinal sectional view of the cap showing the spring pressed plug carried thereby for reception in the bottle neck and for engagement with the sealing disk; and

Figure 6 is a fragmentary longitudinal sectional view showing the cap mounted on the bottle neck.

Referring more in detail to the accompanying drawing, the reference character 10 designates a bottle, preferably formed of glass and having a reduced neck 11 carrying at the open mouth end thereof a relatively thin outwardly directed frangible annular flange 12. An internal annular enlargement 13 is formed on the neck 12 and forms an annular shoulder or seat 14 for a sealing disk 15 of fibrous or any suitable material disposed below the frangible flange 12.

A closure cap 16 of cup-form is closed at its outer end as at 17 while the inner end thereof is open as at 18. A coil spring 19 is confined within the cap 16, one end of the spring 19 being secured to the inner face of the closed end 17 of the cap while the other end of the spring is secured to a plunger or plug 20 that normally projects below the open end 18 of the cap. The plug 20 is of less diameter than the internal diameter of the cap 16 and at the upper end thereof that is attached to the adjacent end of the spring 19 there is formed an annular flange 21 moving in frictional contact with the inner wall of the cap 16. As shown more clearly in Figures 3, 5, and 6, a pair of diametrically opposite lugs 22 depend from the lower open end 18 of the cap, the lugs being outwardly offset as illustrated with the inner faces 23 thereof in the plane of the inner wall of the cap 16, a groove 24 being formed in the inner face of each lug 22 at the inner side 23 thereof. The external diameter of the bottle neck 11 is substantially the same as the internal diameter of the cap 16 and the lugs 22.

To place the cap 16 upon the bottle 10, the open end of the cap is positioned out of longitudinal alignment with the bottle neck 11 to place a side edge of the spring pressed plug 20 in engagement with a side edge of the open end of the bottle neck, the part of the plug engaged with the bottle neck being located at a point between the diametrically opposite lugs 22. Downward pressure on the cap 16 causes the plug 20 to be moved upwardly into the cap and the cap lowered onto the bottle neck and in a position to cause engagement of the open end 18 at one side of the cap with the frangible flange 12 of the bottle neck and to align the grooves 24 in the lugs 22 with the bottle neck flange 12. Lateral sliding movement of the bottle cap causes the grooves 23 in the lugs 22 to receive the bottle neck flange 23 and when the cap 16 has been moved completely in longitudinal alignment with the opening in the bottle neck, the spring 19 will force the plug 20 downwardly into the bottle neck for engagement with the sealing disk 15. In this position, the spring pressed plug 20 prevents separation of the interlocking connection between the frangible flange 12 on the bottle neck and the grooved lugs 22 on the cap 16. To open the bottle, it is necessary to forcibly move the cap into engagement with an object or to percussively strike the cap to cause the latter to break the frangible flange 12 on the bottle neck and to destroy the interlocking connection between the bottle neck flange 12 and cap lug.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:—

10. 1. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
15. 2. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
20. 3. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
25. 4. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
30. 5. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
35. 6. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
40. 7. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
45. 8. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.
50. 9. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, and means carried by the cap for engagement with the neck flange and prevented from separation from the plug by the position of the plug in the bottle neck.

gible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, means carried by the cap for engagement with the neck flange and prevented from separation from the plug by the position of the plug in the bottle neck, said means including diametrically opposite lugs carried by the cap and said lugs being grooved at their inner sides for reception of the bottle neck flange, said plug being in the plane of the connection between the frangible flange and cap.

5. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, means carried by the cap for engagement with the neck flange and prevented from separation from the plug by the position of the plug in the bottle neck, said plug being movable into the cap to permit lateral alinement of the flange engaging means on the cap with said flange whereby the cap is laterally moved into closing position on the bottle neck.

6. In a non-refillable bottle, a bottle having a relatively thin outwardly directed annular frangible flange at the mouth thereof, a sealing disk seated in the neck of the bottle below the frangible flange, a cap adapted for interlocking and non-removable mounting on the bottle, a tensioned plug carried by the cap for reception in the neck of the bottle below the flange of the bottle neck for engagement with the sealing disk, means carried by the cap for engagement with the neck flange and prevented from separation from the plug by the position of the plug in the bottle neck, said means including diametrically opposite lugs carried by the cap and said lugs being grooved at their inner sides for reception of the bottle neck flange, said plug being movable into the cap to permit lateral alinement of the flange engaging means on the cap with said flange whereby the cap is laterally moved into closing position on the bottle neck.
